UNITED STATES PATENT OFFICE.

ENOCH P. STEVENS, OF CHICAGO, ILLINOIS, ASSIGNOR TO LOCOMOTIVE ARCH BRICK COMPANY, OF CHICAGO, ILLINOIS, A CORPORATION OF ILLINOIS.

LOCOMOTIVE-ARCH CONSTRUCTION.

1,090,891.

Specification of Letters Patent. Patented Mar. 24, 1914.

Application filed August 23, 1911. Serial No. 645,643.

To all whom it may concern:

Be it known that I, ENOCH P. STEVENS, a citizen of the United States, residing at Chicago, in the county of Cook and State of Illinois, have invented certain new and useful Improvements in Locomotive-Arch Constructions, of which the following is a specification.

My invention relates to arch constructions, 10 and refers particularly to arches used in locomotive fire boxes.

In practically all locomotives it is customary to employ a series of arch tubes which extend downwardly from the rear 15 water leg of the boiler to the front water leg. These arch tubes act as supports for the fire brick, which compose an arch extending longitudinally of and across the fire box so that the latter is divided into upper 20 and lower portions. By means of this arch the products of combustion are deflected to take a longer course, and thereby act more efficiently in heating the water contained in that portion of the boiler above the fire box, 25 while at the same time the gases reach the boiler tubes at a somewhat lower temperature and thereby prolong the life of the latter.

It is desirable to construct the arch in 30 such manner that when any of the bricks composing the same are burned out they may be readily removed without disturbing the other bricks of the arch, while at the same time these bricks should be securely locked 35 in position so that there may be no danger that they will become displaced while the locomotive is in operation. I accomplish this result by employing two series of bricks, the bricks of one series being adapted to be 40 applied directly to the arch tubes without longitudinal sliding thereon, each of such bricks resting on but a single tube, and the bricks of the second series engaging the bricks of the first series and locking the latter in position on the tubes. The two series 45 of bricks form the arch, and together prevent the passage of gases through said arch. I preferably employ a plurality of rows of bricks, each brick having a recess on its lower portion which is adapted to engage an arch tube. On their upper surfaces the bricks are suitably recessed so that a locking brick 50 may be inserted between adjacent bricks, thereby preventing the latter from

rotating and becoming displaced. By means 55 of this construction, when one or more bricks have been burned out and the locomotive is shut down for repairs, it is only necessary to remove the locking bricks on the two sides of any bricks which is to be removed, and 60 the latter may then be easily taken out of position.

These and other advantages of my invention will be more readily understood by reference to the accompanying drawings, which 65 show preferred embodiments of my improvements, and in which—

Figure 1 is a vertical longitudinal section through the fire box of a locomotive, showing the front arch in position; Fig. 2 is a 70 vertical transverse section taken on the line 2—2 of Fig. 1; Fig. 3 is an enlarged transverse section through a portion of the front arch, showing the manner in which the bricks are held in position on the arch tubes; 75 Fig. 4 is a section similar to Fig. 3, but showing a modified form of construction; Fig. 5 is a vertical section similar to that shown in Fig. 2, but disclosing a modified form of arch construction; Fig. 6 is a perspective of one of the variation blocks used 80 in the arch construction shown in Fig. 5; Fig. 7 is a perspective of one of the side sheet blocks used in the construction shown in Fig. 5; and Fig. 8 is a perspective of one 85 of the filler blocks used in the construction shown in Fig. 5.

The arch tubes 10 extend upwardly from the front water leg 11 to the rear water leg 12, dividing the fire box 13 into an upper 90 portion 14 and a lower portion 15. The boiler tubes 16 extend forwardly from the flue sheet 17 in a well known manner.

In the construction shown in Figs. 1 to 3, inclusive, a row of fire bricks 18 is supported on each of the arch tubes 10, each of these bricks having a recess 19 in its lower surface for the reception of an arch tube 10, as clearly shown in Figs. 2 and 3. The upper surface of each brick 18 is also formed 95 with the two lateral recesses 20 and 21. After the fire bricks have been placed in position on the arch tubes 10, locking bricks 22 may be inserted in the recesses 20 and 21 of adjacent bricks, whereby these bricks are 100 prevented from rotating. The edges of the rows of bricks on the two sides of the arch abut directly against the side sheets 23, and 105

I have found that it is generally unnecessary to employ a locking brick between the two outer rows of bricks and said side sheets.

In Fig. 4 I have shown a somewhat modified form of construction. The bricks 18^a are provided with the recesses 19^a engaging the arch tubes 10. Each brick has a curved side 24 and a top portion 25. The locking bricks 22^a are suitably shaped to conform to the shape of the bricks 18^a and are slipped in position after the bricks 18^a are placed on the arch tubes 10.

It will be apparent that when it is desired to remove any particular brick in the arch 15 of my construction the locking bricks 22^a engaging the two recesses 20 and 21 of the brick are first removed and the brick may then be lifted out of position. The bricks of the same row which are located to the rear 20 of the brick which has been removed may then be allowed to move in a forward direction and a new brick is added to the rear and upper end of the row, and in order to lock it securely in position the locking bricks 25 22^a are then placed in position.

In the modified form of arch construction shown in Figs. 5 to 8, inclusive, the filler blocks 26 are supported against the arch tubes 10 by means of the semi-circular 30 grooves 27. Each of the filler blocks 26 is tilted upwardly, as clearly shown in Fig. 5, and between the filler block edges, which lie intermediate of the arch tubes, are placed the variation blocks 28, each block having 35 an over-hanging edge 29 to prevent it from slipping downwardly. In order to compensate for any variation of distance between the arch tubes 10, the variation blocks 28 are made of varying widths so that the filler 40 blocks 26 are maintained in proper alignment. In the case of the arch tubes 10, which are immediately adjacent to the side sheets 23, the side sheet blocks 30 are used. Each block, as clearly shown in Fig. 7, has 45 a semi-circular groove 31 and an extension 32 which extends substantially to the side sheet 23.

It will be evident that in the modified form of construction just described the arch 50 tubes 10 are efficiently protected from the action of the flame, and blistering is thereby prevented. When it is desired to remove one or more of the filler blocks 26 or side sheet blocks 30, the corresponding variation 55 block 28 is first withdrawn, and the filler

block or side sheet block, as the case may be, may then be readily withdrawn from its engagement with the arch tube.

It will be apparent to those skilled in the art that many changes could be made in the 60 detailed construction of the improved forms of locomotive arches which I have described without departing from the spirit or scope of my invention.

What I claim is:

1. In a locomotive having a fire box therein, the combination of a plurality of arch tubes extending through said fire box, a plurality of rows of bricks supported on said arch tubes, each of said rows being supported on a corresponding arch tube, said bricks having recesses in their lower surfaces for the reception of said arch tubes, and a plurality of rows of locking bricks engaging adjacent rows of bricks and filling the 75 space therebetween, substantially as described.

2. In a locomotive having a fire box therein, the combination of a plurality of arch tubes extending through said fire box, a 80 plurality of rows of bricks supported on said arch tubes, each of said rows being supported on a corresponding arch tube, said bricks having recesses in their lower surfaces and lateral recesses on their upper surfaces, and locking bricks engaging said upper recesses and filling the space between said bricks, whereby the latter are prevented from rotating on said arch tubes, substantially as described.

3. In a locomotive furnace, the combination of a plurality of inclined water tubes, and an arch supported by said tubes, said arch including two series of brick, the brick of one series being supported by said tubes, 95 each brick by a single tube and the brick of the other series being adapted to lock the brick of the first series against rotation upon their respective supporting tubes, each of the brick of the first series being adapted as a 100 whole to be applied to or removed from its respective supporting tube by lateral motion thereof to said tube, and the brick of the two series being arranged to practically exclude the passage of gases therebetween, 105 substantially as described.

ENOCH P. STEVENS.
